MACHINE FOR MAKING WINDOW ENVELOPE BLANKS.

APPLICATION FILED NOV. 14, 1912.

Patented Oct. 17, 1916.

2 SHEETS—SHEET 2.

UNITED STATES PATENT OFFICE.

WILLIAM H. BANZETT, OF BERGENFIELD, NEW JERSEY, ASSIGNOR TO MERCANTILE CORPORATION, OF NEW YORK, N. Y., A CORPORATION OF NEW YORK.

MACHINE FOR MAKING WINDOW-ENVELOP BLANKS.

1,201,430.

Specification of Letters Patent. Patented Oct. 17, 1916.

Application filed November 14, 1912. Serial No. 731,402.

To all whom it may concern:

Be it known that I, WILLIAM H. BANZETT, a citizen of the United States, and a resident of Bergenfield, in the county of Bergen and State of New Jersey, have invented certain new and useful Improvements in Machines for Making Window-Envelop Blanks, of which the following is a specification.

10 This invention relates to machines for making window envelop blanks with a display opening therethrough provided with a transparent covering.

The object of my improvements is to provide means for forming the opening, for applying a patch of transparent paper thereover, for affixing that patch against the borders of the window opening in a continuous web of paper, severing that web 20 into successive envelop blanks in proper relation to the window openings therein, all during the continuous advancement of the web.

25 The machine of this application is adapted for producing envelop blanks in accordance with the subject matter of my copending application for Letters Patent of the United States for improvements in the process of making window envelop 30 blanks, Ser. No. 719380, filed September 9, 1912, and to which reference may be had.

With these ends in view I employ mechanism illustrated in its preferred embodiment in the drawings accompanying this 35 specification wherein—

Figure 1 is a diagrammatic sectional elevation of my improved machine. Fig. 2 is a plan view of the patch cutting and feeding mechanism. Fig. 3 is an enlarged plan 40 view of a portion of a continuous web of paper and of an envelop blank severed therefrom, illustrating the several steps in the production of envelop blanks by my improved machine. Fig. 4 is a diagrammatic 45 side elevation corresponding with Fig. 1 and showing the gearing for driving the several rotative parts of my machine. Fig. 5 is a detail side elevation showing the cutter mechanism for the transparent strip. Fig. 50 6 is a detail enlarged view of the window cutting mechanism. Fig. 7 is an enlarged view of a further detail. Fig. 8 is an elevation of cutting roll 23 viewed from the

right hand side of Fig. 1, and to a larger scale than that of Fig. 1. 55

My improved machine comprises a pair of feed rolls 5, 6 by which the continuous web of paper 4 is led from the usual roll 2 mounted on shaft 3. From rolls 5, 6 said web 4 is passed upwardly over roll 7 and thence to and between rolls 8, 9. Said roll 8 is provided with opposite cutters 28, having suitable profiles for cutting window openings 10 (Fig. 3) in the web, and said cutters are skewed on said roll to position 60 their cuts respectively, as illustrated in said Fig. 3. Roll 9 is preferably a hardened roll 65 for coaction with the cutters on roll 8.

Cutter 28 is provided with barbed spear 30 which, as said cutter coacts with roll 9, 70 punctures the web, and as rolls 8, 9 continue their rotation conducts the window blank away from the web. Said window blank may be removed from spear 30 by means of ejector 32 actuated by fixed cam 33. Adjacent and to the left of rolls 8, 9, Fig. 1, is gumming roll 12 for coaction with plain roll 11 thereunder. Said roll 12 has opposite gummers 34 thereon, each corresponding in profile and in skewed position with 80 gummed portion 13, Fig. 3. Said gum roll may be supplied with gum in the usual manner from gum supply 14 of well known character.

To the left of roll 11, Fig. 1, is a roll of 85 transparent paper 15 and adjacent to said roll is a pair of feed rolls 16 and upper and lower cutting knives 17, 18 respectively. Between said cutting knives and roll 11 are upper and lower patch feed rolls 19, 20 respectively. Said roll 20 preferably has its 90 axis in the same horizontal plane as and parallel with the axis of roll 11 and is situated for coaction therewith to feed the web of paper downwardly as illustrated. Said roll 20 is provided with opposite patch clips 95 21, 22 for gripping the patches successively delivered thereto. Said clips may be urged to their work by springs as 35 to clip 21 and may be lifted by the engagement of 100 their rolls as 37 of said clip 21 with fixed cam 36.

The roll of patch paper 15, feed rolls 16 and cutters 17, 18 are in skewed position 105 relatively to rolls 19, 20, see Fig. 2, so that the successive patches are delivered to roll

20 skewed relatively thereto and in correspondence with the skewed position of windows 10 in web 4. Patch web feed rolls 16 may be geared together by gears as 38 and 5 may be driven from shaft 43 of roll 19 by gearing indicated in a general way by 39.

Cutter 17 may be conveniently pivoted on fixed shaft 46 and oscillated at suitable intervals by cam 47 on shaft 44 through the 10 instrumentality of roll 48 fixed to connector 49, the upper end of which is pivotally attached to the arm of cutter 17.

Below roll 20 is cutting roll 23 for coaction with hardened roll 24 below roll 11 for 15 severing the web into envelop blanks, the sides of each of which preferably form substantially a parallelogram having sides parallel with the sides of the web, as illustrated in Fig. 3, and for cutting notches 25, 20 25 in the edges of the web respectively in suitable relation to the envelop blank. Said roll 23 is of such a diameter and the cutting members are so disposed relatively thereto as to sever two blanks at each revolution.

25 Below rolls 23, 24 is receiving box 31 of some convenient construction for receiving the completed blanks as 27, Fig. 3.

For the present purpose shaft 51 may be considered the driving shaft of the machine 30 and fixed thereto is gear 61 which drives gear 52 on shaft 90 of roll 9; on shaft 80 of roll 8 is fixed gear 53 which meshes with and is driven by gear 52. Gear 55 fixed to shaft 70 is driven from gear 52 through intermediate 54. Gears 58, 59 are fixed to shafts 50, 60 respectively and said gear 58 may be driven from gear 54 through intermediates 56, 57.

Returning to main gear 61, said gear 40 drives gear 62 fixed to shaft 41 and said gear 62 drives gear 63 fixed to shaft 42; gear 64 fixed to shaft 43 is driven by gear 63; fixed to shaft 40 is gear 65 driven by gear 62 and gear 66 of pasting mechanism 14 is driven 45 by gear 65 and in turn drives gear 67 of said pasting mechanism. Gear 69 fixed to shaft 45 is driven from gear 61 through intermediates 71 and 72 and gear 68 fixed to shaft 44 is driven by gear 69.

50 While I have herein illustrated the transparent patch paper as fed from a continuous web and cut into portions as needed for use I do not wish to limit myself to the illustrated details of that mechanism as various 55 modifications thereof may be had by those skilled in the art without departing from the spirit and scope of my improvements.

The practice of my improved process is as follows: Web 4 being fed in the direction 60 of its arrow over roll 7 and between rolls 8, 9, the window opening 10 is cut therein by cutting roll 8 in coaction with lower roll 9 and the perforated web is fed forwardly over roll 11, whereupon gummer 12 deposits 65 onto the upper face of said web, gum 13

about said window opening 10. During these several steps rolls 16, 16 have fed forwardly over knife 18 a suitable length of transparent patch paper 26 and thereupon clip 21 grips the leading end of said patch strip and simultaneously knife 17 descends and severs the patch length from the web. Roll 20 in its continued rotation then delivers said patch portion against the gummed window border of the web and as said web 70 and patch pass between rolls 11, 20 the patch is squeezed down onto the web and by means of the gum, affixed thereto. The downwardly moving web then passes between cutting roll 23 and plain roll 24 whereby the 75 envelop blank profile is cut and the completed blank 27 is delivered into hopper 31.

It will be understood that my improved machine is a continuously operating one, the several rotary members being maintained 85 in constant rotation, whereby a product greatly increased over that to be had in intermittently operating machines may be had.

I claim:

1. A machine for making from a continuous web of material a series of window envelop blanks the sides of each of which form substantially a parallelogram having sides parallel with the sides of the web including in combination, means for continuously advancing the web, means for cutting a series of windows skewed relatively to the longitudinal dimension of the web and in predetermined successive positions therein, means for applying gum to one face of said web about the borders of each window, and means for delivering a patch in skewed position relatively to the web in register against the gummed borders of the window therein. 90

2. A machine for making window envelop blanks from a continuous web of material including in combination, means for continuously advancing the web, means for cutting a series of windows skewed with respect to the line of travel of the web and in predetermined successive positions therein, means for conducting the window blanks away from the web, means for applying gum to one face of said web about the borders of each window, and means for delivering a patch in skewed position relatively to the web in register against the gummed borders of the window therein. 100

3. A machine for making window envelop blanks from a continuous web of material including in combination, means for continuously advancing the web, means for cutting a series of windows skewed relatively to the longitudinal dimension of the web and in predetermined successive positions therein, means for applying gum to one face of said web about the borders of each window, means for advancing a web of transparent paper in a direction skewed rela- 115

- tively to the first mentioned web, means for cutting a patch portion from the leading end of said transparent web, and means for delivering said patch portion in skewed position relatively to the first mentioned web in register against the gummed borders of the window therein.
4. A machine for making window envelop blanks from a continuous web of material including in combination, means for continuously advancing the web, means for cutting a series of windows skewed relatively to the longitudinal dimension of the web and in predetermined successive positions therein, means for applying gum to one face of said web about the borders of each window, means for delivering a patch in skewed position relatively to the web in register against the gummed borders of the window therein, and means for cutting the envelop blank from the web.
5. A machine for making window envelop blanks from a continuous web of material including in combination, means for continuously advancing the web, means for cutting a series of windows skewed relatively to the longitudinal dimension of the web and in predetermined successive positions therein, means for applying gum to one face of said web about the borders of each window, means for delivering a patch in skewed position relatively to the web in register against the gummed borders of the window therein, and means for cutting the envelop blank from the web.
6. A machine for making window envelop blanks from a continuous web of material including in combination, means for continuously advancing the web, means for cutting a series of windows skewed relatively to the longitudinal dimension of the web and in predetermined successive positions therein, means for conducting the window blanks away from the web, means for applying gum to one face of said web about the borders of each window, means for advancing a web of transparent paper in a direction skewed relatively to the first mentioned web, means for cutting a patch portion from the leading end of said transparent web, means for delivering said patch portion in skewed position relatively to the first mentioned web in register against the gummed borders of the window therein, and means for cutting the envelop blank from the web.
7. A machine for making, from a continuous web of paper, a series of window envelop blanks, the sides of which form substantially a rhomb shaped parallelogram having two sides parallel with the path of the web and having the major axis of the blank at an angle to the side of the web, including, in combination, means for continuously advancing the web of paper, means for severing the web in a diagonal direction to the longitudinal dimension of the web, means for cutting a plurality of window apertures in the paper, said apertures extending in a parallel direction to the major axis of the blank, means for gumming the paper around the pre-cut window apertures, means for applying patches to be secured by the gum to cover the aforesaid windows, and means for coöordinating the operations of the said feeding, aperture cutting, gumming, severing and patch applying devices whereby the apertures are properly registered upon the blanks and whereby the gum and the patches are properly registered over the borders of the pre-cut windows.
8. A machine for making from a continuous web of material a series of window envelop blanks the sides of each of which form substantially a parallelogram having sides parallel with the sides of the web including in combination, means for continuously advancing the web; means for cutting a series of windows skewed with respect to the longitudinal dimension of the web and in predetermined successive positions therein; means for applying gum to one face of the material about the borders of the said windows and means for delivering a patch to register with the gummed borders of the pre-cut window.
9. In an envelop machine, the combination of means for continuously feeding a web of paper; means for cutting window openings in said moving web in a skewed direction with respect to the line of travel of the said web, with continuously operating means for supplying a succession of patches to said web, said patch supplying means being adapted to supply the said patches diagonally upon and at an angle to the direction of travel of the web whereby the patches are properly applied over the window openings, and means for coöordinating the operation of the feeding, window cutting and patch applying means whereby the windows and the patches are properly registered one with the other and are properly positioned upon the moving web.
10. In a machine of the class described, in combination, means for continuously advancing a web of paper; means for severing the web into rhomb shaped blanks, means for cutting oblong window apertures in said web, the major axis of said oblong aperture being parallel with the major axis of the rhomb blank when severed from the web; and means for successively applying patches to the paper to cover the aforesaid apertures.
11. In a window envelop blank machine; a mechanism for applying a transparent patch to an opening in an envelop blank forming part of a continuous strip and in which the opening is skewed with respect to the longitudinal dimension of the strip,

comprising in combination a pair of rolls between which the continuous strip is passed whereby pressure is applied to said strip, means for advancing a strip of transparent material and presenting said strip to one of said rolls in a path inclined to the axis of the said roll, a gripping means on one of said rolls adapted to grip the leading end of the angularly approaching strip of transparent paper, means for severing the said transparent strip to form a patch and

means for releasing the said gripping mechanism after the severed patch has been carried into the bight of the said rolls.

Signed at New York, in the county of 15 New York and State of New York, this 12th day of November, 1912, before two subscribing witnesses.

WILLIAM H. BANZETT.
